DOOR HINGE AND SUPPORT

James R. Haley, New York, N. Y., assignor to Welbilt Stove Company, Inc., Maspeth, Long Island, N. Y., a corporation of New York

Application September 8, 1936, Serial No. 99,766

6 Claims. (Cl. 126—191)

This invention relates to hinge constructions and more particularly to a hinge and support for oven doors and the like.

An object of the invention is to provide an improved form of hinge and support for an oven door, whereby the door may be readily removed for any desired purpose such as cleaning, repair or the like.

A feature of the invention relates to an oven door having a hinge structure whereby the door is fastened to the body of the stove or range entirely by readily removable links, thus avoiding the use of screws and bolts which as is well-known tend to rust or corrode rendering it difficult eventually to remove the door.

Another feature relates to an oven door having an improved hinge structure and latch support wherein the sheet metal cover acts to lock the hinge pintles in place.

A further feature relates to an improved form of hinge pintle for an oven door hinge.

A still further feature relates to the novel organization, arrangement and relative location of parts which go to make up an improved and simple hinge and support for oven doors and the like.

Other features and advantages not specifically enumerated will be apparent after a consideration of the following detailed description and the appended claims.

In the drawing, Fig. 1 is a plan view, partly sectional, of part of a stove and oven door embodying features of the invention.

Fig. 2 is a left-hand elevational view of Fig. 1.

Fig. 3 is a sectional view of Fig. 1 taken along the line 3—3 thereof.

Fig. 4 is a sectional view of Fig. 1 taken along the line 4—4 thereof.

Fig. 5 is a detail view of part of the door construction.

Inasmuch as the hinge and supporting structure is duplicated at both sides of the door, only one hinge and latch support is illustrated in the drawing. Accordingly referring to Fig. 1 the numeral 1 represents the usual vertical angle iron forming part of the usual oven door frame, it being understood that a similar angle iron is provided at the left-hand end of the door frame. The two vertical angle members are connected by the horizontal metal member 2 which forms the lower sill for the door. In accordance with usual construction metal sheeting 3 is fastened to the frame of the stove to enclose the sides thereof. Fastened in any suitable manner, for example by rivets 4, to the horizontal frame mem-

ber 2, is a metal bracket 5 having an integral arm 6 bent at right angles and passing through the aperture 7 in member 2, it being understood that a similar bracket is provided at the left-hand end of the member 2. The forward end of each arm 6 is provided with a round opening to receive the hinge pintles according to the invention.

The oven door is indicated generally by the numeral 8 and is preferably formed from a rigid metal casting having its edges upturned to form a shallow dish-shaped frame, the upturned edges of one corner of which are indicated in the drawing by the numerals 9 and 10. The edge 10 is provided with a slot to allow the arm 6 to extend therethrough. Welded or otherwise fastened to the edge 10 and to the bottom wall of the door 8 is a metal bracket 11 having the formation as shown in detail in Fig. 5. As shown clearly in Figs. 1 and 5 this bracket is provided with an upturned flange 12 which is welded to the edge 10 of the door frame, and also with an upturned flange 13 which is welded to the edge 9. The flange 13 is formed with an inwardly offset tongue 14 having a circular opening 15 adapted to be disposed in alignment with the similar opening in the arm 6 to receive the hinge pintle 16. Another upright flange 17 is formed on the bracket and provided with an opening 18 to receive the hinge pintle 19. The bracket 11 is also provided with a right-angled flange 19a having a threaded opening 20 to receive a screw 21, (Figs. 3 and 5), for fastening the sheet metal cover plate 22 in place. It is understood of course that the drawing shows only one corner of the door and that brackets similar to bracket 11 are provided at the three remaining corners so that the cover plate 22 may be firmly screwed to the door frame.

For the purpose of limiting the extent of opening of the door to a substantially horizontal position, there is provided a curved hanger and latch member 23 at each side of the door. As shown more clearly in Figs. 1 and 2 the member 23 is formed with a substantially circular shaped body portion terminating at its upper end in a latching projection 24 which is adapted to engage the frame 1 to limit the downward opening movement of the door, and for this purpose the said frame member 1 is provided with a slot 25 through which the latch member passes. Member 23 is provided at its lower end with a circular opening adapted to be in alignment with the opening 18 for the purpose of receiving the hinge pintle 19 as shown more clearly in Fig. 1. Member 23 is also formed with an offset arm 26 having an opening in its forward end in alignment with the opening 16 and 55

the opening in arm 6, to receive the hinge pintle 16. As shown clearly in Fig. 1 each of the hinge pintles is in the form of a right-angled rod and the pintles are arranged to be assembled so that the portions 27 and 28 are in alignment, but preferably the portion 28 is slightly longer than the corresponding portion 27 so that when the pintles are assembled as shown in Fig. 1 the portion 28 partially overlies the portion 27. As will be clear from the showing of Fig. 1 the pintles are locked against side-wise movement by engagement with the vertical part 29 of the flange 19. As an additional precaution against dislocation of the pintles the bracket 11 is formed with an upright flange 30 which together with the flange 29 defines a locking channel of about the same width as the pintle portion 28. The pintles are locked against rotation by reason of the cover plate 22, when the latter is fastened in place on the oven door frame by screws 21.

In order to hold the door tightly closed there may be provided a tension spring 31 anchored at its lower end to the frame of the stove, and coupled at its upper end to the latch member 23 as shown in Fig. 2, it being understood that the parts are so proportioned that the door can remain in its horizontal open position against the tension of spring 31. From the foregoing description it will be seen that there is provided a relatively simple hinge support for the oven door, and the only screws necessary to effect complete assembly of the hinge structure and door on the stove are the screws 21 which hold the cover plate 22 in place. Should it become necessary at any time to remove the door the removal can be effected very expeditiously since all that is necessary is to remove the screws 21 which are very easily accessible when the door is in a horizontal open position. When the face plate 22 is removed, it is merely necessary to rotate the pintles 16 and 19 until they clear the flange 19 whereupon they may be easily removed without employing any special tools for the purpose.

While one particular embodiment has been illustrated and described, it will be understood that various changes and modifications may be made therein without departing from the spirit and scope of the invention.

What I claim is:

50 1. A supporting hinge structure for an oven door or the like, comprising a stationary frame member, a pair of arms projecting from said member each arm having a pintle receiving opening a pair of brackets fastened to at least two 55 corners of the door each bracket having a pair of upturned lugs with pintle receiving openings, and another pair of lugs to form a pintle locking channel, a plurality of pairs of right-angled pin-

5 tles each of said pintles having part of its length disposed in a locking channel, and a cover plate for the door to prevent dislocation of the pintles from said channels.

2. A supporting hinge structure for an oven 5 door and the like, comprising a stationary frame, a pintle receiving arm projecting from said frame, a pair of pintle receiving lugs fastened to the door, a pair of right-angled pintles, a latch member having a pair of pintle receiving openings in alignment with the pintle receiving openings in said lugs, a locking channel carried by said door in which the opposed ends of the pintles are disposed to prevent sidewise movement thereof, and a cover plate for said door arranged 15 to limit the rotational movement of said pintles.

3. A supporting hinge structure for an oven 20 door and the like, comprising a stationary frame member, a pair of pintle receiving arms projecting from said member, a pair of brackets fastened to the door and each having a pair of lugs defining a channel a plurality of pairs of right-angled pintles each pintle having part of its length disposed in a channel to lock it against sidewise movement, a latch member slidably 25 passing through a slot in said frame member, said latch member having pintle receiving openings, and a cover plate removably fastened to said door to lock said pintles against dislocation 30 from said channels.

4. A supporting hinge structure for an oven 35 door and the like, comprising a stationary frame member having a pintle receiving arm fixedly projecting therefrom, a bracket fastened to the door and having a pair of pintle receiving lugs disposed lengthwise along the side of the door, a hinge pintle in the form of a right-angled bar having one arm passing through said fixed arm and through one of said lugs, a door link having a pintle receiving opening at its forward end and a retractile spring fastened to its rearward end, a second pintle in the form of a right-angled bar having one arm passing through the pintle opening in said link and through the other of said 40 lugs, means defining a channel to receive the other arms of both said pintles, and a cover plate fastened to said door to prevent dislocation of both pintles from said channel.

5. A supporting hinge structure according to 45 claim 4 in which the said other arms of the pintles are in overlapping end relation.

6. A supporting hinge structure according to 50 claim 4 in which the means for defining said channel includes an arm on said bracket said arm having a bent back lug to receive a fastening member for said cover plate.

JAMES R. HALEY.
